H. MILLARD,
ADJUSTABLE UNIT VISIBLE CARD INDEX.
APPLICATION FILED OCT. 23, 1915.

Patented Jan. 3, 1917.

UNITED STATES PATENT OFFICE.

HENRY MILLARD, OF CHICAGO, ILLINOIS.

ADJUSTABLE-UNIT VISIBLE-CARD INDEX.

1,210,670.

Specification of Letters Patent. Patented Jan. 2, 1917.

Application filed October 23, 1915. Serial No. 57,898.

To all whom it may concern:

Be it known that I, HENRY MILLARD, a citizen of the United States, residing at Chicago, in the county of Cook and State of Illinois, have invented new and useful Improvements in Adjustable-Unit Visible-Card Indexes, of which the following is a full, clear, and exact description.

My invention relates to what is known as adjustable visible index-card units comprising a number of interlocking strips of card-board and means for mounting the same.

The object of my invention is to provide a series of such cards having a centering tongue, and a horizontal slit or mouth, and interlocking, by virtue of the tongue of the superposed cards entering the slits of the cards immediately below the same in such manner that the cards cannot have independent lateral movement and are supported parallel to each other by the card units below them.

Another object of my invention is to provide a convenient frame for mounting the card units so that their own resistance to the position in which they are set will automatically hold them in position; to provide them with means for facilitating the separation of a series of cards at any point to permit of the withdrawal or the insertion of one or more card units whenever desired, and to provide a lifter element that is useful when it is desired to close the gap resulting from said separation.

These and other objects I accomplish by the means hereinafter fully described, and as particularly pointed out in the claims.

In the drawings: Figure 1 is a front view of one of the frames in which my improved card units are assembled. Fig. 2 is a vertical section of the same taken on dotted line 2-2, Fig. 1. Fig. 3 is a horizontal section of the same taken on dotted line 3-3, Fig. 1, and drawn to a larger scale. Fig. 4 is a front view of one of said card units removed from its frame. Fig. 5 is a similar view of a group of said units. Fig. 6 is a perspective view of a clamp used in connection with said cards when in the frame. Fig. 7 is a rear view of the lifter used in connection therewith.

The index card units A correspond in design and construction, and each consists of a comparatively narrow strip of stiff paper or card-board or other suitable material having a broad tongue *a* projecting down

from the center of the lower edge thereof, the side edges of which converge at corresponding angles to a point *b* which latter is intersected by an imaginary vertical line 60 striking through the center of length of the card. Above this tongue the card is provided with a mouth *B* consisting of a longitudinal slit which is not quite as long as the width of the root of the tongue and 65 has its ends *c*, *c*, cut downward at a corresponding incline and then parallel to the side edges of the card again in alinement with each other. Cutting the mouth in this manner forms a lip, as it were, and when the 70 tongue of the card above is inserted in this mouth until the horizontal lower edge thereof rests in the lower ends of the downturned ends of the same, the horizontal edge of the card above will be parallel with those of the 75 card now being described, and said lip will lap back of the tongue of the superposed card and will prevent independent end movement of said cards.

The supporting frame in which a series 80 of these interlocked index cards are mounted is practically flat and comprises vertical sheet metal members 2, 2, which constitute the sides of the frame and top and bottom horizontal sheet metal members 3, 3, that 85 constitute the top and bottom of the same. The vertical members 2, 2, preferably, consist of two corresponding vertically elongated sheet metal strips of sufficient width, which are secured flat against each other by 90 riveting or otherwise so as to bring their longitudinal edges together, and these longitudinal edges are bent away from each other back over the sides thereof to form longitudinal guideways 4, 4. The opposite 95 vertical edges are bent forward and rearward at right angles to the sides to provide lateral flanges 5, 5, that are secured together and inclosed within a metal envelop 15, and these flanges extend the entire length of the 100 side members except for about one-half an inch at the ends thereof where they are cut away.

The upper and lower members 3, 3, of the frame each consists of a strip of metal which 105 is doubled to bring the longitudinal edges thereof together and inclose within the bend a wire or metal rod 6. These rods extend beyond one side of the frame and have their extremities 7 bent toward each other 110 to form pintles or pivotal pins that are journaled in bearings in a suitable stand

(not shown). The upper and lower ends of side members 2, 2, are inserted between the lapping portions of the upper and lower members of the frame and are riveted or otherwise secured thereto in such relative positions that the rolled edges or guide-ways 4, 4, will constitute the outer vertical edges of said frame and will lap outside of the end edges of the upper and lower members 3, 3, and the flanges 5, 5, thereof will be separated a distance about as shown and will constitute the vertical edges of the vertically elongated opening of said supporting-frame. The index card units are mounted in this frame by inserting one end edge thereof under one guide-way and the opposite end edge thereof under the opposite guide-way of the same. The flanges 5, 5, keep the medial portion of said index card units bowed outward, and thus cause the ends of said units to press outward against the outer side of the guide-ways to such an extent that the friction between said ends and the outer overlapping portion of the guide-ways will hold said units against independent movement when they are not disturbed.

The card units are connected in the manner hereinbefore explained when they are mounted in the supporting-frame, but I prefer to support the units in each frame by a lifter 8. This lifter is shown in front elevation in Fig. 1 and in rear elevation in Fig. 7, and consists of a strip of celluloid or other suitable material, which is folded longitudinally along its center line to bring its longitudinal edges together and to form lips 9, 9, that are riveted together by ordinary eyelets 10, 10, such as are used for fastening strips of paper together. The lowermost card unit in the frame is inserted between the lips of this lifter, and the tongue thereof extends down between the eyelets, as shown in dotted lines in Fig. 1, and in order to stiffen this lifter 8, I insert in the bend thereof below the eyelets a strip of elastic steel 11, which is straight except at its ends 12, which latter are bent obliquely to a slight extent in the same direction. The ends of lifter 8 and the spring strip 11 are inserted in the guide-ways and the ends of said strip are sprung and insure the retention of the lifter in any vertical position to which it may be adjusted in the supporting-frame.

I also prefer to use a clamp 13 in connection with my improvements that consists of a strip of spring metal, similar to strip 11 used in the lifter. This clamp may be sprung into position at the top of the series of card units, as shown in Fig. 1 of the drawings, or, when it is desired to remove or insert a card unit at any point the ends of this clamp are inserted in the guide-way over the card unit just above where the insertion or withdrawal is desired. The finger

nail of the operator is caught over the upper edge of this unit and the series of cards below are pushed downward a distance corresponding to the width of a card unit. The ends of the card unit to be inserted are then sprung into position under the guide-ways, or in such position that the point of the tongue thereof can be moved down back of the upper edge of the card unit engaged by the finger nail and will enter the mouth of the latter unit until the lower edge of the inserted unit rests against the portions e, e, of slit B of the unit so engaged by the finger nail. The clamp is then removed and the superposed portion of the series of card units are pushed downward and made to engage the units below so as to fill up the gap in the manner hereinbefore described, and as shown in the drawings. If it is desired to remove one of said card units, the same manner of separating the series at the point where the withdrawal is desired is adopted, as when an insertion is to be made, and the unit is then withdrawn first by moving it upward and then outward until its ends move out of the guide-ways, and then the gap caused by the removal of said index is closed in the manner hereinbefore described.

What I claim as new is:

1. A card having a depending tongue and a slit a portion of the length of which is offset; the slit being located between the tongue and the upper edge of the card into which the tongue of a superimposed card is adapted to be inserted, and the offset portion of said slit being less in length than the distance between the ends thereof. 95
2. A card having a depending tongue and a slit; said tongue extending laterally from the body portion of the card and the portion formed in the card by the slit being narrower at its mouth than at its base to produce a lip which projects from the plane of the card when the tongue of a superimposed card is inserted within the slit. 105
3. The combination of a series of horizontally disposed cards, in combination with a frame in which the same are mounted, and a lifter device which supports said cards and is arranged and has its ends confined in the same frame in which said cards are seated. 115
4. A card having a slit and a depending tongue; the slit being formed in the card between the tongue and the upper edge of the card; the uppermost portion of the slit forming a lip, and the tongue being produced by a depending portion of the card below the lip formed by the slit. 120
5. The combination with a series of horizontally disposed cards each having interlocking tongues and mouths or slits, in combination with a frame in which the same are mounted having means in which the ends of said cards are retained and adapted to bow 125 130

the medial portion of said cards outward, and a flat strip of spring steel the ends of which are adapted to engage and be inserted in said guideways.

5 6. The combination with a series of horizontally disposed cards each having interlocking tongues and mouths or slits, in combination with a frame in which the same are mounted having means in which the 10 ends of said cards are retained and adapted to bow the medial portion of said cards outward, and a flat strip of spring steel the ends of which extend obliquely and are adapted to engage and be inserted in said 15 guide-ways.

7. The combination with a series of horizontally disposed cards each having interlocking tongues and mouths or slits, in combination with a frame in which the same are 20 mounted having means in which the ends of said cards are retained and adapted to bow the medial portion of said cards outward, and a lifter device the ends of which engage and are inserted in said guideways and in

which the lowermost of said series of cards 25 is seated.

8. The combination with a series of horizontally disposed cards each having interlocking tongues and mouths or slits, in combination with a frame in which the same are 30 mounted having means in which the ends of said cards are retained and adapted to bow the medial portion of said cards outward, and a lifter device consisting of a strip of 35 suitable material folded to bring its longitudinal edges together and suitably spaced apart, eyelets for riveting said lapping portions together; the lowermost unit of said series of cards being seated between the lapping portions of said lifter and the tongue 40 thereof entering between said eyelets.

In witness whereof I have hereunto set my hand this 18th day of October, 1915.

HENRY MILLARD.
